CLAIM

The ornamental design for a bathroom article support post for towel bars and the like, as shown and described.

DESCRIPTION

FIG. 1 is a top, front, and right side perspective view of a bathroom article support post for towel bars and the like showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 9 is a top, front, and right side perspective view thereof, with the broken-line disclosure of a towel bar and display plate being for illustrative purposes only and forming no part of the claimed design;

FIG. 10 is a reduced top, front, and right side perspective view of a second embodiment thereof, with the broken-line disclosure of a towel bar being for illustrative purposes only and forming no part of the claimed design; and,

FIG. 11 is a reduced top, front, and right side perspective view of a third embodiment thereof, with the broken-line disclosure of a display plate being for illustrative purposes only and forming no part of the claimed design.
